UNITED STATES PATENT OFFICE.

ALFRED W. MORGAN, OF LONGBEACH, CALIFORNIA, ASSIGNOR OF ONE-FOURTH TO LEWIS M. WOOD, OF LONGBEACH, CALIFORNIA.

TROLLEY-POLE.

SPECIFICATION forming part of Letters Patent No. 760,641, dated May 24, 1904.

Application filed November 16, 1903. Serial No. 181,386. (No model.)

To all whom it may concern:

Be it known that I, ALFRED W. MORGAN, a citizen of the United States, residing at Longbeach, in the county of Los Angeles and State 5 of California, have invented a new and useful Trolley-Pole, of which the following is a specification.

This invention relates to trolleys, and one of the principal objects thereof is to provide 10 a pole which will materially assist in maintaining a constant contact between the trolley and the conductor even when traveling at a high rate of speed, so that the oscillation of the moving car will not affect the uniform 15 contact between the trolley and the conductor-wire.

A further object of the invention is to permit the elevator-pole to drop below the conductor under certain conditions, so as to prevent 20 contact of the pole or harp with any of the guy-wires or any other obstruction.

A further object of the invention is to yieldingly support the pole, the yieldability of which can be destroyed mechanically.

25 Another object of the invention is to provide means for permitting the pole to automatically drop below the conductor-wire and at the same time support said pole above the car.

30 Further objects and advantages of this invention will appear in the following description, and the novel features thereof will be particularly pointed out in the appended claims, it being understood that changes in the form, proportion, and the minor details 35 of construction may be resorted to without departing from the spirit or sacrificing any of the advantages of the invention.

Figure 1 is a view, partly in elevation and 40 partly in plan, of the device applied. Fig. 2 is a similar view after the levers have been tripped. Fig. 3 is a vertical cross-sectional view through the base and car-top, taken on line 3-3 of Fig. 1. Fig. 4 is a fragmentary 45 top plan view of one of the levers, showing rollers carried thereby. Fig. 5 is an end view of the lever illustrated in Fig. 4. Fig. 6 is a vertical sectional view of the sliding sleeve and the lever for the trolley-supporting harp.

Fig. 7 is a view in side elevation of a modified form of trolley-harp and a portion of the pole. Fig. 8 is a similar view of a further modified form of harp, and Fig. 9 is a like view of an additional form of trolley-harp. Fig. 10 is a detail rear elevation with the trolley-pole in section, illustrating the disposition of the upper portion of the trigger to lie out of the path of the downward movement of the trolley-pole.

Referring now to the drawings by numerals 50 of reference, 1 designates the top of a car, to which is reversibly secured a base 2, forming a support for the trolley-pole and the mechanism used therewith. The trolley-pole 3 is pivoted between the parallel standards 4 and 5 and carries at one end a trolley-harp 6, having parallel ears 7, through which projects a shaft 8, carried by the pole and on which the harp can rock. The usual trolley 9 is mounted in the harp at a point above the pivot thereof and is supported above the pole by a lever 10, movable on the reduced end 3^a of the pole by a collar 10^a, between which and the shoulder 3^b is a spring 11, having a tendency to force the lever 10 outward, so as to maintain 60 the trolley in constant contact with the conductor. Suitable mechanism is also provided for normally holding the harp-carrying end 70 of the pole in elevation, and this mechanism is illustrated as comprising a plurality of 75 spring-controlled levers, one of which is designated as 12 and fulcrumed at 13. One end of the lever 12 is connected to the pole by a coil-spring 14, while the other end is connected to a second lever 15, horizontally-disposed and 80 carrying a link-lever 16, which is connected to the lever 12 and offers a pull to the end of the lever 12 remote from the end connected to the spring, so as to normally hold the spring 85 under tension. The position of the lever 90 12 will be governed by the position of the lever 15, which is provided with a bifurcated terminal 15^a, in which is a roller 17, normally engaged by a spring-trigger having a shoulder 18 resting over the top of the roller, so 95 that the link-lever 16 will have a tendency to pull one end of the lever 12 against pull of the spring 14 and so as to throw one end of

the lever 12 away from the pole and cause the spring 14 to be under tension.

The trigger is connected to the arm of the trolley-harp by a connection 19, so that in 5 the event of the trolley "jumping the conductor" the arm 10 of the harp would be moved beyond its normal position to such an extent that the yielding end of the trigger will be unseated, causing the lever 15 to move upward and permit one end of the lever 12 to move toward the pole, so as to destroy the tension of the spring 14 and permitting the harp-carrying end of the pole to drop below the conductor-wire and below the guy-wires, 15 thereby preventing any accident due to contact of the trolley and other obstructions. It will be observed that the pole is yieldably but independently mounted and when in its normal position the tendency will be to keep 20 the trolley in constant contact with the conductor, so as to obviate the loss of current due to continuous vibration of the trolley, which is of considerable annoyance and expense in roads employing the present style of 25 trolley.

The antifriction-roller 17 is carried by the bifurcated end of the lever 15, so as to reduce friction during the engagement and disengagement of the trigger with the lever 15, and in 30 order to permit the lever 15 to easily ride upon the lower edge of the pole 3 the terminal arms 20 are arranged to lie on either side of the lever 15, thus facilitating the restoration of the several parts of the mechanism to 35 their normal position.

Inasmuch as the trolley-harp will have a considerable latitude of movement on the pole, the trolley will not "jump" owing to the usual vibration or swaying of the car, as do 40 the ordinary constructions of trolleys, and the lever mechanism carried by the base 2 will not be actuated except under a very unusual circumstance. However, when the pole is vibrated beyond the limit of movement of the 45 arm of the harp the trigger 18 will be automatically drawn out of engagement with the lever 15, permitting the pole to fall, as above described. The spring 14 will expand sufficiently to permit the pole to drop the necessary 50 distance below the wire and will contact with the antifriction devices on the end of the lever 15, but will not bear thereon to any considerable extent.

To reset the trigger, the pole 3 is drawn 55 down by means of the cord 31 and presses on the lever 15, forcing it down into engagement with the shoulder or lip 18 of the trigger, and the tension of the spring will then cause the pole to move upward into operative position.

60 It will here be explained that the upper end portion of the trigger above the shoulder 18 is bent or offset laterally to one side of the vertical path of the trolley-pole 3, so that when the latter is being drawn down to reset 65 the trigger it will pass at one side of the up-

per portion of the trigger, and the roller 17 will engage with the shoulder 18 before the trolley-pole reaches the same, wherefore it will be understood that the top of the spring-trigger is disposed so as not to interfere with the resetting of the apparatus. 70

The form of harp illustrated in Fig. 7 comprises an arm 21, carried by the pole, with the trolley mounted in the free end thereof, the opposite end terminating in a depending arm 75 22, connected to the cord 19, and between the arm 22 and the pole a coil-spring 23 is interposed to normally hold the trolley in contact with the wire.

In Fig. 8 the form illustrated comprises a 80 terminally-pivoted harp 24, carrying the usual trolley at the end opposite the pivoted terminal and intermediately connected to the cord 19, a spring 25 being interposed to preserve the normal contact of the trolley and the 85 conductor-wire.

In Fig. 9 the form of harp is similar to that shown in Fig. 8, but in lieu of the spring 25 a pair of spring-pressed toggles 26 and 27 are employed, which are secured, respectively, to 90 the pole and the harp and connected by a collar 28, slideable on a finger 29, pivotally carried by the pole and around which is wound a coil-spring 30, exerting pressure against the collar 28. The cord 31 is designed for the purpose of pulling down upon the harp to restore the several parts to their normal positions. 95

It will be noted that by the lever 10, combined with the spring 11, a uniform pressure will be exerted upon the conductor-wire, because as the tension of the spring decreases, due to expansion, the leverage of the lever 10 will proportionally increase, so that the liability of the trolley jumping the wire will be remote. 100

Having thus described my invention, what I claim is—

1. The combination with a pivoted pole, of a lever mechanism for holding the pole suspended and comprising two levers, one of which is connected to the pole and the other lever having link connections attached to the first-named lever. 110

2. The combination with a pivoted pole, of a lever, means connected with said lever to hold the pole in an elevated position, a trigger connected with said lever and a connector device on the pole for automatically releasing the trigger. 115

3. The combination with a trolley-pole, of an intermediately-pivoted lever, one end of which is connected to the pole, a second lever, means on the second lever to engage the first lever and means engaging the second lever to hold the first-named lever in a position to support the pole. 120

4. The combination with a trolley-pole, of an intermediately-pivoted lever, one end of which is connected to the pole, a second lever, a means on the second lever to engage the first- 125

named lever, and means connected with the free end of the pole for automatically releasing the levers to permit the pole to drop.

5. The combination with a pivoted trolley-pole of a plurality of connected levers, one of which is connected to the pole by a spring and one of which normally maintains the tension of the spring, and means connected with the free end of the pole and with one of said levers for relieving the tension of the spring.

6. The combination with a pivoted trolley-pole of a plurality of connected levers, one of which is connected to the pole by a spring and another of which normally maintains the tension of the spring, and a trigger for destroying the tension of the spring.

7. The combination with a pivoted trolley-pole, of a mechanism for normally holding the pole elevated, a pivoted harp on the pole and connected to the mechanism, and a spring-pressed lever connected to the pole and the

harp for exerting pressure against the harp to release the mechanism and permit the pole to drop.

8. The combination with a trolley-pole, a pivoted harp on the pole, a lever movable longitudinally on the pole and connected to the harp and a tension-spring exerting pressure against the lever.

9. The combination with a trolley-pole having a reduced end, a pivoted harp carried by the pole, a sliding collar on the reduced end of the pole, a lever connected to the collar and to the harp, a coil-spring around the pole and bearing against the collar.

In testimony that I claim the foregoing as my own I have hereto affixed my signature in the presence of two witnesses.

35 ALFRED W. MORGAN.
